UNITED STATES PATENT OFFICE

114,166

DESIGN FOR A FOLDING TYPE CLOSET BOWL AND MOUNTING THEREFOR

Leif Andersen and Edward A. Fredrickson, Chicago, and Thomas P. Newman, Geneva, Ill., and Hugh R. Van Sciver, Trenton, N. J., and Roy H. Zinkil, Oak Park, Ill.

Application June 18, 1938, Serial No. 77,920

Term of patent 14 years

To all whom it may concern:

Be it known that we, Leif Andersen, Edward A. Fredrickson, Thomas P. Newman, Hugh R. Van Sciver and Roy H. Zinkil, citizens of the United States, the said Andersen residing at East 110th and South Cottage Grove Avenue, in the county of Cook, city of Chicago, State of Illinois; the said Fredrickson residing at 5956 Manton Avenue, in the county of Cook, city of Chicago, State of Illinois; the said Newman residing at 503 First Street in the county of Kane, city of Geneva, State of Illinois; the said Van Sciver residing at 309 N. Clinton Avenue, in the county of Mercer, city of Trenton, State of New Jersey, and the said Zinkil residing at 406 N. Cuyler Avenue, in the county of Cook, village of Oak Park, State of Illinois, have invented a new, original and ornamental Design for a Folding Type Closet Bowl and Mounting Therefor of which the following is a specification, reference being had to the accompanying drawings, forming part thereof.

Fig. 1 is a side perspective view of the folding type closet bowl and mounting therefor showing our new design.

Fig. 2 is a front view of the folding type closet bowl and mounting therefor with the closet bowl in its raised position.

Fig. 3 is a plan view of the folding type closet bowl and mounting therefor with the bowl in its lowered position.

Fig. 4 is a rear view of the folding type closet bowl and mounting therefor.

Fig. 5 is an opposite side perspective view of the folding type closet bowl and mounting therefor.

We claim:

The ornamental design for a folding type closet bowl and mounting therefor, substantially as shown and described.

LEIF ANDERSEN.
EDWARD A. FREDRICKSON.
THOMAS P. NEWMAN.
HUGH R. VAN SCIVER.
ROY H. ZINKIL.
